Patented Aug. 12, 1969

214,975

MEDICAL LIQUID CONTAINER

Elmer F. St. Amand, North Hollywood, Calif., assignor
to American Hospital Supply Corporation, Evanston,
Ill., a corporation of Illinois

Filed Nov. 12, 1968, Ser. No. 14,410

Term of patent 14 years

Int. Cl. D24—02; D9—01

U.S. Cl. D83—1

FIG. 1.

FIG. 2.

FIG. 3.

FIG. 4.

FIGURE 1 is a front elevational view of the medical liquid container showing my new design, the undisclosed rear being a mirror image of the front;

FIGURE 2 is a right side elevational view, the undisclosed left side being a mirror image of the right side;

FIGURE 3 is a bottom plan view; and

FIGURE 4 is a top plan view.

I claim:

The ornamental design for a medical liquid container, as shown and described.
